SINGLE HANDLE CONTROL

Ernest C. Carlson, Hinsdale, Marvin D. Jennings, Naper-
ville, and Robert W. Woodring, La Grange, Ill., as-
signors to International Harvester Company, Chicago,
Ill., a corporation of Delaware

Filed June 30, 1969, Ser. No. 17,960

Term of patent 14 years

Int. Cl. D8—03

U.S. CL. D8—152

FIG. 1 is a side elevational view of the single handle control in association with a tractor and backhoe;

FIG. 2 is a perspective view of the control as viewed from one side; and

FIG. 3 is a perspective view of the control as viewed from the opposite side.

The portions shown in broken lines on the drawing are included for illustrative purposes only.

We claim:

The ornamental design of a single handle control, sub-
stantially as shown and described.
